UNITED STATES PATENT OFFICE

JOSEPH B. STRAUSS, OF SAN FRANCISCO, CALIFORNIA

DESIGN FOR A HIGHWAY BRIDGE PIER

Application filed January 2, 1932. Serial No. 42,352. Term of patent 14 years.

To all whom it may concern:

Be it known that I, JOSEPH B. STRAUSS, a citizen of the United States of America, residing at San Francisco, in the county of San Francisco and State of California, have invented a new, original, and ornamental Design for Highway Bridge Piers, of which the following is a specification, reference being had to the accompanying drawings, forming a part thereof.

Fig. I is a front elevation of a highway bridge pier, showing my new design, and

Fig. II is an end elevation of the same.

I claim:—

The ornamental design for a highway bridge pier, substantially as shown.

JOSEPH B. STRAUSS,
